(57) **CLAIM**

The ornamental design for portable light handles, as shown and described.

DESCRIPTION

FIG. 1 is a front perspective view of the claimed handles folded down in the nondeployed configuration as rotatably attached to a portable search shown in dotted outline.

FIG. 2 is a left side plan elevational view of the handles of FIG. 1 in the folded nondeployed configuration.

FIG. 3 is a right side plan elevational view of handles of FIG. 1 in the folded nondeployed configuration.

FIG. 4 is a top plan elevational view of the handles of FIG. 1 in the folded nondeployed configuration.

FIG. 5 is a bottom plan elevational view of the handles of FIG. 1 in the folded nondeployed configuration.

FIG. 6 is a rear end elevational view of the handles of FIG. 1 in the folded nondeployed configuration.

FIG. 7 is a front end elevational view of the handles of FIG. 1 in the folded nondeployed configuration.

FIG. 8 is a front perspective view of the claimed handles of the present invention as shown in FIG. 1, but with the handles moved upward into a locked deployed position suitable for man grasping of the handles with the portable light shown in dotted outline.

FIG. 9 is a left side plan elevational view of the handles of FIG. 8 in the deployed configuration.

FIG. 10 is a right side plan elevational view of the handles of FIG. 8 in the deployed configuration.

FIG. 11 is a top plan elevational view of the handles of FIG. 8 in the deployed configuration.

FIG. 12 is a bottom plan elevational view of the handles of FIG. 8 in the deployed configuration.

FIG. 13 is a rear end elevational view of the handles of FIG. 8 in the deployed configuration; and,

FIG. 14 is a front elevational view of the handles of FIG. 8 in the deployed configuration.

The broken line represents portions of the article not claimed and forms no part of the claimed design.

1 Claim, 14 Drawing Sheets
